UNITED STATES PATENT OFFICE.

LOUIS N. PERKINS, OF CONNERSVILLE, INDIANA.

ROTARY BLOWER OR PUMP.

1,082,903.

Specification of Letters Patent. Patented Dec. 30, 1913.

Application filed February 26, 1913. Serial No. 750,825.

To all whom it may concern:

Be it known that I, LOUIS N. PERKINS, a citizen of the United States of America, residing at Connersville, in the county of Fayette and State of Indiana, have invented certain new and useful Improvements in Rotary Blowers or Pumps, of which the following is a specification.

This invention relates to rotary blowers, or pumps, and it has for its object the provision of an improved device of this character constructed in such manner as to reduce friction between the working parts to a minimum, provide for the efficient oiling of all working parts, provide a device consisting of so few parts that the maximum of economy may be achieved and one constructed in such manner that the device may be very readily and easily assembled.

Further objects and advantages of the invention will be set forth in the detailed description which now follows.

In the accompanying drawings, Figure 1 is a view partly in side elevation and partly in section of a blower constructed in accordance with the invention. Fig. 2 is a view partly in end elevation and partly in section thereof. Fig. 3 is a detailed end elevation of the rotor. Fig. 4 is a detailed perspective view of one of the rollers hereinafter described. Fig. 5 is a detailed perspective view of a guide hereinafter described, and Fig. 6 is an inner face view of one of the cap plates of the blower.

Like numerals designate corresponding parts in all of the figures of the drawings.

Referring to the drawings it will be seen that the blower comprises a casing 5 having an intake port 6 and a discharge port 7 formed therein. Cap plates 8 and 9 have annular channels 10 formed in their inner faces, said channels being eccentrically arranged with relation to the bearings of the main shaft 11. This shaft is supported in bearings comprising rings 12 and 13 and balls 14. Ring 13 is supported by a collar 15, said collar being supported in turn by ribs 16 from cap plate 8. A rotor 17 is secured to the shaft and rotates therewith. This rotor is recessed at its opposite ends, as indicated at 18, for the reception of the guides 19 shown in Fig. 5. These guides carry arcuate ribs 20 which travel in channels 10. The channels 10 while being located eccentrically with relation to shaft 11 is located concentrically with relation to the

interior of casing 5, and the shaft 11 is located concentrically with relation to the rotor 17. Screws 21 pass through the upper portions of the guides 19 and enter the ends of blades 22. It will therefore be seen that the outer edges of these blades are caused to lie in proximity to the inner periphery of casing 5 during the bodily rotation of the guides and blades as hereinafter set forth. 60 This bodily rotation is imparted to the guides and blades by the rotor 17, said rotor having a plurality of recesses 24 formed therein for the reception of rollers 25, said rollers having the necessary oscillatory motion in the seats formed by said recesses. The blades 22 are seated in radial slots 25^a formed in the rollers and have sliding movement in said slots. An oil chamber 26 is formed centrally in the rotor and an oil port 70 75 leads longitudinally through the shaft to said chamber. The rollers are provided with ports 28 which at certain times during the rocking movement of said rollers are brought into communication with ports 29 80 formed in the rotor and leading to the oil chamber 26. This alignment of ports 28 and 29 takes place when the particular roller affected, is at the bottom of the casing 5 and at this time a limited amount of oil is supplied to the blades 12 to render their sliding action within the rollers free and easy. This oil also finds its way about the periphery of the rollers and lubricates said rollers during their rocking or oscillatory movement. 85 90

The structure herein shown presents a number of very important advantages, while comprising few and simple elements. These elements impart the necessary positive movement to the blades to maintain their outer edges in conjunction with the inner periphery of the casing 5 without at the same time forcing said parts into actual contact with said periphery. The friction is correspondingly reduced. The peculiar arrangement 95 of parts shown for accomplishing this result renders the device capable of being easily and readily assembled. The guides lie within the recessed ends of the rotor and act in conjunction with the blades to impel 100 the air or other fluid through the casing 5. The oiling arrangement shown and described while maintaining a liberal supply of oil always available, permits the passage of this oil to the working parts only 110 during a limited portion of the cycle of operation, so that the lubricant is not wasted,

and what is more important, it is not supplied in such liberal quantity as to be thrown out of the discharge port. It will also be noted that the body of the rotor is solid, 5 and the recessing of its ends provides means in which to mount the guides. The provision of a solid rotor while rendering this part comparatively heavy, insures the smooth and steady run of the device, because 10 the inertia of this solid rotor causes it to act much after the manner of a balancing wheel.

The portion of the guides carrying the arcuate ribs and said arcuate ribs each fill substantially one-third of the annular channels 10, so that the ends of these parts abut each other and any tendency of the ribs to 15 drag and bind in these channels is prevented.

While the elements shown and described 20 are well adapted to serve the purposes for which they are intended, it is to be understood that the invention is not limited to the precise construction set forth, but includes within its purview, such changes as may 25 be made within the scope of the appended claims.

Having described my invention, what I claim is:—

1. In a device of the character described, 30 the combination with a casing, a shaft eccentrically mounted with relation thereto, a rotor disposed within said casing and carried by said shaft, an oil chamber formed within said rotor, means for conducting oil through said shaft to said chamber, there being a plurality of arcuate recesses formed in the said rotor and opening to the outer face thereof, rollers seated in said recesses, said rollers having radial slots formed therein and said 35 rollers having rocking movement in said recesses, ports formed in said rollers and ports formed in said rotor, said latter port establishing communication between the ports of the rollers and said oil chamber at 40 a predetermined point in the travel of the rotor and means disposed between said blades and a portion of said casing for causing the outer edges of said blades to travel in close relation to the inner periphery of 45 said casing throughout the rotation of the rotor.

2. In a device of the character described,

the combination with a casing, a shaft eccentrically mounted with relation thereto, a rotor disposed within said casing and carried 55 by said shaft, an oil chamber formed within said rotor, means for conducting oil through said shaft to said chamber, there being a plurality of arcuate recesses formed in the said rotor and opening to the outer face 60 thereof, rollers seated in said recesses, said rollers having radial slots formed therein and said rollers having rocking movement in said recesses, ports formed in said rollers and ports formed in said rotor, said latter 65 port establishing communication between the ports of the rollers and said oil chamber at a predetermined point in the travel of the rotor, guides secured to said blade and arcuate ribs carried by said guides there being 70 an annular channel formed concentrically with one of the end walls of the casing within which said ribs engage.

3. In a device of the character described, 75 the combination with a casing, a shaft eccentrically mounted with relation thereto, a rotor disposed within said casing and carried by said shaft, an oil chamber formed within said rotor, means for conducting oil through said shaft to said chamber, there 80 being a plurality of arcuate recesses formed in the said rotor and opening to the outer face thereof, rollers seated in said recesses, said rollers having radial slots formed therein and said rollers having rocking movement 85 in said recesses, ports formed in said rollers and ports formed in said rotor, said latter port establishing communication between the ports of the rollers and said oil chamber at a predetermined point in the travel of 90 the rotor, guides secured to said blade and arcuate ribs carried by said guides, there being an annular channel formed concentrically with one of the end walls of the casing 95 within which said ribs engage, the ends of said rotor being recessed for the reception of said guides.

In testimony whereof I affix my signature in presence of two witnesses:

LOUIS N. PERKINS.
